UNITED STATES PATENT OFFICE.

JULIUS KAHN, OF DETROIT, MICHIGAN, ASSIGNOR TO TRUSSED CONCRETE STEEL COMPANY, OF DETROIT, MICHIGAN, A CORPORATION OF MICHIGAN.

FLOOR CONSTRUCTION.

1,033,413.

Specification of Letters Patent. Patented July 23, 1912.

Application filed October 17, 1910. Serial No. 587,420.

To all whom it may concern:

Be it known that I, JULIUS KAHN, a citizen of the United States, and a resident of Detroit, in the county of Wayne and State 5 of Michigan, have invented a new and Improved Floor Construction, of which the following is a specification.

This construction relates to reinforced concrete floors, especially to floors formed 10 by joists or beams crossing each other, combined with continuous slabs, and the object of this invention is to provide forms or centers for supporting the concrete forming these slabs and to act as molds for the joists.

15 This invention is embodied in pressed sheet-metal forms or centers, preferably substantially rectangular, having corrugated sides.

In the accompanying drawings, Figure 1 20 is a perspective showing a floor construction embodying this invention. Fig. 2 is a plan of a sheet of metal properly cut to go to the forming die. Fig. 3 is an elevation and Fig. 4 is a bottom plan of a finished center. Fig. 25 5 is an elevation of a modified form of the same.

Similar reference characters refer to like parts throughout the several views.

Hollow terra-cotta tiles have been employed as molds, centers or fillers to form 30 hollows or air-spaces in reinforced concrete floors, with a large measure of success. Where tiles can be procured at reasonable prices, such construction is probably one of the most 35 desirable yet devised. But the weight of the tiles and the resultant cost of shipping the same precludes their use at any great distance from the place where they are burned. The sheet metal centers shown in the drawings 40 may be pressed at a single action of a forming die and then shipped "nested" at a moderate cost. For centers twenty-four inches square at the bottom and from six to eight inches high, sheet steel of No. 28 U. S.

45 standard gage is usually sufficiently heavy. Before the sheet 1 (Fig. 2) is pressed, notches 2 may be cut in opposite edges to receive the ribs of ribbed - metal - lath as shown in Fig. 1. The sheet is then pressed 50 to form a center 3, (Figs. 2 and 3) the corrugations 4 in the sides running from maxi-

mum at the edges to nothing at the top. The sides of the centers, by reason of these corrugations, are of sufficient stiffness to carry the load of the slab and of the workmen and their tools and barrows. 55

When a floor is to be constructed, a false work is built and the centers are properly positioned; the concrete is placed between them to support the reinforcements, the reinforcements are positioned and the concrete filling completed. When a flat ceiling is desired, as shown in Fig. 1, a metal-lath is laid directly on the falsework. The centers 60 3 are then positioned, and if a ribbed-lath 65 5 is employed, the ribs 6 will enter the notches 2, thus alining the centers. Concrete is placed in the bottom of the spaces between the centers and reinforcing bars 7 and 8 are laid thereon; after which the remainder of the concrete 9 is filled in and 70 rolled down.

The metal centers 3 are preferable to tiles because the sides are all closed, admitting no concrete, and permitting reinforcement 75 in both directions because concrete joists crossing each other are possible. This ideal reinforcement of a floor admits of the use of much lighter metal. The concrete beams are laterally braced at frequent intervals and 80 may therefore be quite light. As the floor slabs are supported by the forms or centers 3 and by crossed joists, the thickness can be reduced to a minimum, effecting great saving of concrete and producing a very 85 light floor. Usually a square center or form is most desirable, but when oblong forms are desired, the construction shown in Fig. 5 may be employed, two sections 12 and 13 being shown constructed with but three 90 sides 14, and with their open ends over-lapping. Because of the corrugations, the two sections will be rigidly united. If desired, the metal may be pressed to form these oblong centers of any desired size, but the 95 standard sizes will probably all be square. After the concrete has set, the false-work may be removed and plaster 15 applied to the lower surface of the metal lath. The concrete at the bottom of the joists will 100 flow around the strands and meshes of the lath and lock it firmly in place.

Having now explained my construction, what I claim as my invention and desire to secure by Letters Patent is:—

In a floor construction, the combination of a properly spaced series of rows of sheet metal members comprising rectangular tops and corrugated sides, the lower edges of two opposite sides having notches, a sheet of expanded metal extending below said members and formed with parallel ribs extending upwardly into the notches in the edges

of the members and thereby alining the members in parallel rows, and a body of concrete extending over and between the members. 15

In testimony whereof I have signed this specification in the presence of two subscribing witnesses.

JULIUS KAHN.
